UNITED STATES PATENT OFFICE.

RAYMOND HARVEY, OF NEW YORK, N. Y., AND HARRY V. DAY, OF PEQUANNOCK TOWNSHIP, MORRIS COUNTY, NEW JERSEY, ASSIGNEES TO THE PANTASOTE LEATHER COMPANY, OF PASSAIC, NEW JERSEY, A CORPORATION OF NEW JERSEY.

PROCESS FOR ORNAMENTING SHEET MATERIAL.

No Drawing.

Application filed July 1, 1926. Serial No. 119,984

The present invention relates to a process for coloring sheet material to produce ornamental effects, and particularly to the ornamentation of flexible sheets such as fabrics, 5 paper and the like.

It has been proposed heretofore to ornament sheet materials by placing a pattern or stencil against the material and then applying a stenciling color by means of a spray 10 gun, the outline or pattern of the design being defined upon the material in this manner. This process has been performed with a single 15 color or with several colors depending upon the effect desired, in either event the principal result sought and obtained being a coloring of comparatively high intensity immediately adjacent the edge of the stencil and becoming less intense as the distance from the stencil edge increases.

20 One of the greatest objections to the ornamentation of materials by this process is that the edge of the design adjacent the stencil is ragged and irregular instead of being sharp and clean-cut. This irregular outline 25 results from the fact that it is almost impossible to maintain the entire stencil or pattern in close contact with the material, and wherever this is not done the color runs under the stencil. In fact, the outline is sometimes irregular even where the pattern is in direct 30 contact for the reason that the color spreads under the pattern due to the differences in absorptive qualities of the material at various localities, this being perhaps aggravated by 35 the capillary attraction of the color molecules to pull the color under the stencil.

While it is exceedingly difficult to eliminate the irregular outline resulting from spraying the color against a pattern, it has 40 been discovered that the ornamental effect is greatly enhanced by the application of a cloud coat containing a metallic or other color after the spraying operation. The effect of such a coating is to produce a general diffused 45 effect, and to eliminate all sharp changes and contrasts in the design of the pattern, this producing a new and pleasing subdued and diffused appearance which is especially effective when the material is to be subsequently 50 embossed and treated with a Spanish coat. In addition, the cloud coat serves to either render the jagged edges resulting from the spraying operation invisible or to so minimize

the appearance thereof as to make their presence scarcely noticeable. The cloud coat may 55 be applied by atomizing with a spray gun, or may be put on under a spreading knife of any well known construction in a manner clearly understood by those skilled in the art.

In addition to the function of clouding or 60 diffusing the color, the cloud coat also functions as a protective coating. However, if desired, a protective coating can also be put on as an entirely separate operation after the cloud coat has been applied and dried. Such 65 a protective coating may consist of any well known ingredients such as pyroxylin containing suitable solvents.

After the application of the cloud and protective coats (if the latter be independently 70 applied), the material may be embossed in any desired manner depending upon the final effect desired and the use to which the material is to be placed.

As a final step after the embossing operation, a Spanish coat can be applied. A Spanish coat is a coat of pyroxylin with the necessary oils, colors and solvents incorporated therein. This coat is spread upon the embossed coated surface in such manner that it 80 coats only the impressions formed by the embossing, leaving the raised portions comparatively free of such additional coating. This coat generally consists of another color suitably contrasting with the colors in the coats 85 previously applied, bringing out and making more pronounced the embossed pattern by means of the contrast in color, and may be applied by means of a spreading knife.

While in the application of the main stenciling color the stencil or pattern may be advantageously used and will produce highly satisfactory results if positioned directly against the material in the customary manner, we have discovered that new and unusual 95 results can be also obtained if the stencil is maintained out of contact with or in spaced relation to the goods and the stenciling color sprayed against the stencil while the latter is so positioned. This produces a very fine 100 shading effect, as the outline of the pattern then becomes vague and ill defined rather than sharp and clean-cut as when the stencil is in direct contact with the material. When the material is stenciled in this manner, it is 105 subsequently treated with a cloud coat and a

protective coat in the manner described above in connection with the directly contacting stencil.

Preferably the stenciling color should contain a suitable fixing means in order to permanently bind the color to the material and prevent the color from wearing off or cracking during use. Examples of suitable fixing means are the solvents commonly used in coating pyroxylin on cloth such as amyl or ethyl acetate and the oils used to keep such coatings soft, as, for example, castor oil, and used at the same time for mixing the colors and introducing them into the pyroxylin. The fixing means permanently bind the color to the material and prevent wearing off or cracking of the color during use. It is immaterial to the successful operation of the present invention whether the flexible material or base has been previously coated to provide a suitable background or not, and it is to be understood that the invention can be successfully used in either case.

Having described the invention, what we claim as new and desire to secure by Letters Patent of the United States is:

1. A process for ornamenting flexible sheet material which consists in covering the material with a pattern or stencil, spraying a color containing a fixing means against the stencil or pattern, and applying a coat over the entire material to cloud over sharply defined irregular outlines and to produce a diffused effect thereon.
- 35 2. A process for producing a shading-off color effect on fabric which consists in holding a stencil over the fabric and in spaced

relation thereto, spraying a color containing a fixing means over the edge of the pattern, and applying a coat over the entire material to cloud over sharply defined and irregular outlines, and to produce a diffused effect thereon.

3. A process for producing a shading-off color effect on flexible sheet materials which consists in holding a stencil or pattern over the material, spraying a color containing a fixing means against the pattern, covering the entire material with a cloud coating to produce a diffused effect, and subsequently applying a protective coat to the fabric.

4. A process for producing a shading-off color effect on fabric and the like, which consists in holding a stencil or pattern over the fabric, spraying a color containing a fixing means over the edge of the pattern, covering the entire fabric with a cloud coating to produce a diffused effect, subjecting the coated fabric to an embossing operation, and thereafter applying a Spanish coat to the fabric.

5. A process for producing a shading-off color effect on fabric and the like, which consists in holding a stencil or pattern over the fabric and in spaced relation thereto, spraying a color containing a fixing means over the edge of the pattern, covering the entire fabric with a cloud coating to produce a diffused effect, subjecting the coated fabric to an embossing operation, and thereafter applying a Spanish coat to the fabric.

In testimony whereof we have hereunto set our signatures.
